DESIGN FOR A POWER DRIVEN TRACTOR

Edward H. Remde, Cleveland, Ohio, assignor to
The Baker-Raulang Company, Cleveland, Ohio,
a corporation of Ohio

Application July 31, 1947, Serial No. 140,643

Term of patent 14 years

(Cl. D14—3)

To all whom it may concern:

Be it known that I, Edward H. Remde, a citizen of the United States, residing at Cleveland, in the county of Cuyahoga and State of Ohio, have invented a new, original, and ornamental Design for a Power Driven Tractor, of which the following is a specification, reference being had to the accompanying drawings, forming part thereof.

Fig. 1 is a side elevation of a power driven tractor, showing my new design;

Fig. 2 is a side elevation, looking at the opposite side of the tractor;

Fig. 3 is a plan view;

Fig. 4 is a rear end elevation;

Fig. 5 is a front elevation; and

Fig. 6 is a perspective view.

The characteristic features of my design reside in the portions shown by means of full lines in the drawings.

I claim:

The ornamental design for a power driven tractor, as shown and described.

EDWARD H. REMDE.
